TURBINE REGULATING MEANS

Filed Feb. 23, 1929

Inventor:
Reginald G. Standerwick,
by *Charles D. Ullan*
His Attorney.

UNITED STATES PATENT OFFICE

REGINALD G. STANDERWICK, OF MARBLEHEAD, MASSACHUSETTS, ASSIGNOR TO GENERAL ELECTRIC COMPANY, A CORPORATION OF NEW YORK

TURBINE-REGULATING MEANS

Application filed February 23, 1929. Serial No. 341,918.

The present invention relates to elastic fluid turbine installations wherein there are provided a main turbine driven alternating current generator or generators which constitute the main source of power and which set the frequency of the system, and a secondary or auxiliary turbine driven alternating current generator which is tied in with the main turbo-generator or generators whereby its speed is fixed, and which may be controlled normally by an operating condition other than the load which it carries, that is, by a means other than its speed governor. For example, the secondary or auxiliary turbine 15 may be an extraction turbine, a back pressure turbine, or a combination of the two and may be regulated normally in terms of extraction pressure or back pressure or both, turbines of this type being now well known in the art. One object of my invention is to provide an improved construction and arrangement in a turbine installation of the type referred to wherein the secondary or auxiliary turbine, which is normally controlled by a means responsive to a condition other than its speed, will be changed over automatically to speed governor control in case the frequency of the system to which it is connected decreases below a predetermined value, whereby such turbine will function to help supply the load and thereby maintain the frequency of the system.

A further object of my invention is to provide an improved system wherein the secondary or auxiliary turbo-generator is connected to secondary or auxiliary bus bars to which is connected a certain load, the secondary or auxiliary bus bars being connected to the main bus bars of the main turbo-generator or generators, and wherein in case the frequency of the system decreases below a predetermined value, the secondary or auxiliary bus bars will be segregated from the main bus bars, the load on the secondary or auxiliary bus bars being then carried by the secondary or auxiliary turbine.

Other objects of my invention and the novel features thereof will be pointed out more fully hereinafter, and for a consideration of what I believe to be novel and my invention

attention is directed to the following specification and the claims appended thereto.

In the drawing, the figure is a diagrammatic view of a turbine installation or system embodying my invention.

Referring to the drawing, 1 indicates an elastic fluid turbine having an admission conduit 2 and an exhaust conduit 3. Turbine 1 may be of any suitable type. In the present instance I have illustrated an impulse turbine of the type termed usually a back pressure turbine, this term being applied to the turbine because during normal operation it is controlled by the pressure of the exhaust elastic fluid. It is to be understood, however, that this type of turbine is illustrated only by way of example and that my invention may be carried out in connection with turbines of other types such as, for example, turbines of the extraction type.

The valve means for controlling the flow of elastic fluid to turbine 1 is indicated at 4. It is here shown diagrammatically and by way of example as comprising a single valve member connected by a stem 5 to a lever 6 pivoted on a fulcrum 7, the free end of lever 6 being provided with a roller 8 which is engaged by a cam 9 carried by a cam shaft 10. It is to be understood that this valve structure is intended to represent any suitable turbine valve gear. On the end of cam shaft 10 is a pinion 11 which meshes with a rack 12 on the upper end of a rod 13. Rod 13 is connected to a piston 14 located in a cylinder 15. Piston 14 is biased toward the lower end of the cylinder by a spring 16. When piston 14 moves upward in the cylinder, cam shaft 10 is turned in a direction to open valve means 4, while when the piston moves downward in cylinder 15, cam shaft 10 is turned in a direction to permit valve means 4 to move toward closed position.

Turbine 1 is shown as being directly connected to an alternating current generator 17 connected by lead wires 18 to bus bars 19, which may be termed secondary or auxiliary bus bars. The secondary or auxiliary bus bars 19 are connected by lead wires 20 to main bus bars 21 to which are connected one or more alternating current turbine driven gen-

erators 22. Turbo-generators 22 may be the main turbo-generators of a power system and are controlled to set the frequency of the system. In connections 18 is a suitable circuit breaker 23, and in connections 20 is a suitable circuit breaker 24. Each of these circuit breakers comprises, in addition to the usual blades for opening the line wires, an additional blade 25 adapted when the switch is closed to bridge a pair of contacts 26. When circuit breakers 23 and 24 are opened, blades 25 move from engagement with contacts 26. Associated with circuit breaker 24 is a trip coil 27 which when energized effects the opening of circuit breaker 24.

Connected to exhaust conduit 3 is a branch conduit 28 which may lead to atmosphere or other suitable point. In conduit 28 is a pressure relief valve 29 which may be set to open at a desired pressure and which functions to prevent the pressure in conduit 3 from exceeding a predetermined high value. Any suitable form of relief valve may be used.

At the lower right hand portion of the drawing, 30 indicates the oil tank for the turbine, 31 indicates the oil pump which supplies oil under pressure for lubricating the turbine and also for supplying pressure to actuate the valve mechanisms, and 32 indicates the oil strainer for pump 31. Pump 31 is provided with a vertical shaft, on the upper end of which is a worm wheel 33 driven by a worm 34 on the end of turbine shaft 35. Also driven by the vertical pump shaft is a suitable speed governor 36.

The parts just described are not shown in correct relative relation to turbine 1, but are shown diagrammatically and as having been brought around into the plane of the paper. This is for the purpose of showing diagrammatically the connections of the parts of the regulating mechanism to each other. As will be understood by those familiar with elastic fluid turbines, the parts will be suitably arranged in combination with the turbine in a usual and convenient manner. It will be understood, also, that the relative sizes of the parts are not correctly shown, the size of some of the parts being greatly exaggerated for purposes of illustration.

Speed governor 36 has its weight arms 37 connected by a stem 38 to a pilot valve 39 provided with upper and lower valve heads 40 and 41. Stem 38 is preferably connected directly to pilot valve 39 so that the pilot valve rotates with the speed governor. When weights 37 fly outward, pilot valve 39 is pulled downward, while when they move inward, pilot valve 39 is moved upward.

Surrounding pilot valve 39 is a pilot valve bushing 42 provided with annular grooves 43 and 44 controlled by valve heads 40 and 41, and with passages 45. Surrounding bushing 42 is pilot valve casing 46 provided with three spaced annular grooves with which

grooves 43 and 44 and passages 45 respectively communicate. Bushing 42 can move axially in casing 46 but cannot turn therein, being held from turning by a suitable spline (not shown). The upper annular groove in casing 46 is connected by a pipe 47 to a pilot valve casing 48; the middle annular groove is connected by a pipe 49 to cylinder 15 beneath piston 14; and the lower annular groove communicates directly with oil tank 30. Pilot valve bushing 42 is connected by a stem 50 to a lever 51 mounted on a fulcrum 52. Stem 50 is shown as being constructed in two parts united by a long nut 53 having threads in its bore and gear teeth on its outer surface. The upper part of stem 50 is pivotally connected to the upper end of nut 53 and the lower part of stem 50 is threaded and engages with the threads of nut 53. Meshing with the gear teeth on nut 53 is a gear wheel 54 connected by beveled gears 55 to a synchronizing motor 56. In these connections is a friction clutch 56^a of suitable construction, through which motor 56 drives nut 53. The total movement of pilot valve bushing 42 is limited by a pin 56^b which engages stops 56^c. When pin 56^b engages a stop 56^c, clutch 56^a slips so as to avoid stalling the motor. When motor 56 turns in one direction, nut 53 is turned to shorten the length of stem 50, while when motor 56 turns in the opposite direction, nut 53 is turned to increase the length of stem 50, thereby raising and lowering pilot valve bushing 42. This diagrammatic showing of motor 56 in connection with stem 50 is intended to represent any suitable synchronizing arrangement. In particular, I may use an arrangement such as that disclosed in the patent to Scott No. 1,583,610, patented May 4, 1926.

The left hand end of lever 51 is connected by a link 57 to one end of a lever 58 pivoted on a fulcrum 59. The other end of lever 58 is connected to rod 13. Fulcrum 59 is supported by the plunger 60 of an electromagnet, the winding of which is indicated at 61. When winding 61 is energized plunger 60 is held against a stationary stop 61^a, whereby fulcrum 59 is held stationary. Beneath the fulcrum of lever 58 is an adjustable stop 62 which limits downward movement of lever 58 when winding 61 is deenergized. Connected to lever 58 is a spring 63 which tends to pull lever 58 down into engagement with stop 62.

The right hand end of lever 51 is connected to one end of a floating lever 64. The other end of floating lever 64 is connected by a stem 65 to a pilot valve 66 located in pilot valve casing 48. Pilot valve 66 has two valve heads 68 and 69. Valve head 68 cooperates with an annular groove 70 in pilot valve casing 48 and valve head 69 cooperates with an annular groove 71 in the pilot valve casing. Connected to annular grooves 70 is a pipe-line 72 which communicates with

the discharge side of pump 31. 73 is a suitable non-return valve arranged in this pipeline and 74 is a pressure relief valve which may be set to relieve the pressure on the discharge side of pump 31 whenever it exceeds a predetermined high value. 74^a indicates the conduit through which oil is supplied from an auxiliary source for use in starting the turbine. Annular groove 71 may communicate with any suitable discharge region. Lever 64 is connected by a link 75 to one end of a lever 76. The right hand end of lever 76 is pivotally connected to a stem 77 which at its lower end carries a piston 78 which moves in a cylinder 79. On stem 77 is a threaded portion 80 on which is an adjustable bushing 81. Mounted on bushing 81 in a manner such that the bushing may turn in it is a spring clamp 82 which is attached to one end of a spring 83, the other end of the spring being attached to a spring clamp 84 fixed to the top of cylinder 79. Spring 83 serves to oppose upward movement of piston 78 and may be adjusted to load the piston to the desired extent. Connected to stem 77 is an arm 85 to which is connected a contact 86 adapted to bridge a pair of contacts 87 carried by insulating housing 88.

Lever 76 is pivotally mounted on a fulcrum 89 connected to the plunger 90 of an electromagnet, the winding of which is indicated at 91. When winding 91 is energized, plunger 90 is held against a stationary abutment 92. Connected to lever 76 is a spring 93 which, when winding 91 is deenergized, serves to lift lever 76, turning it on the upper end of stem 77 as a fulcrum. Windings 91 and 61 are connected in series with a suitable source of electrical energy 94. The circuit may be traced as follows:

Upper lead line 94, conductor 95, solenoid winding 91, conductor 92^a, solenoid winding 61, conductor 93^a, contacts 94^a and bridge piece 95^a of a contact-making frequency-responsive instrument (described hereinafter), conductor 96, contacts 26 and contact blade 25 of circuit breaker 24, conductor 97, hand switch 98, contacts 26 and contact blade 25 of circuit breaker 23, conductor 99, and fuse 100 to the lower lead line 94. When windings 61 or 91 are energized, the corresponding plungers, having been moved to the positions shown in the drawing, will be held thereby the windings. When the windings 61 are deenergized, however, and the springs 63 and 93 have moved levers 58 and 76, in the one case into engagement with stop 62 and in the other case to the limit of the movement of pilot valve 66, neither will be moved back to its prior position when windings 61 and 91 are again energized. They must be moved back manually in order to restore them to their former positions. The pull of the windings 61 and 91, when energized, while sufficient to hold the plungers in the position

shown in the drawing, is not sufficient to move them to such positions after they have been moved away by springs 63 and 93.

101 indicates a contact making ammeter having a movable contact arm 102 adapted to engage either of two pairs of contacts 103 and 104, or to stand in a position intermediate between such contacts. 105 indicates the winding of contact making ammeter 101. This winding is connected by conductors 102^a to line wires 18 of generator 17, the connection being made through a suitable current transformer 106. With this arrangement, the current flowing through ammeter winding 105 is proportional to the load on generator 17. In conductors 102 is a load adjusting shunt connected resistance 107.

108 and 109 indicate the two field windings of synchronizing motor 5^c. Winding 108, when energized, operates motor 56 in a direction to lower bushing 42; and winding 109, when energized, operates motor 56 in a direction to raise bushing 42. One side of winding 108 is connected by a conductor 108^a to one of the contacts 103, the other contact 103 being connected by a conductor 110 to one of the contacts 87. One side of winding 109 is connected by a conductor 111 to one of the contacts 104, the other contact 104 being connected by a conductor 112 to the upper line of energy source 94. The other terminals of windings 108 and 109 are connected through the armature of motor 56 to the lower line of source of energy 94 by a conductor 113. The other terminal 87 is connected by a conductor 114 to conductor 112. 115 is a hand switch connected to conductor 112 and adapted to be moved into engagement with either contact button 116 or contact button 117.

Trip coil 27 of circuit breaker 24 is connected to source of energy 94 by conductors 118 and 119, the conductor 119 including a pair of contacts 120 adapted to be bridged by bridge piece 121, and a fuse 121^a.

The lower end of cylinder 79 is connected by a pipe-line 122 to exhaust conduit 3 of turbine 1, whereby piston 78 is subjected to the pressure of the exhaust elastic fluid of turbine 1. When the exhaust pressure in conduit 3 increases piston 78 will be moved upward against the action of spring 83, while when the exhaust pressure in conduit 3 decreases, spring 83 will move piston 78 downward.

Bridge pieces 95^a and 121 are carried by a stem 123 which is moved by a suitable type of instrument responsive to the frequency of the system to which the alternating current generators 22 are connected. Any suitable type of frequency responsive instrument may be utilized, the essential thing being that, when the frequency decreases below the desired value, in the first instance the circuit including contacts 94^a will be opened, and when the frequency decreases still further bridge piece 121 connects together contacts 120. In the

present instance I have indicated a frequency responsive instrument of the type disclosed in my application Serial No. 314,917, filed of even date herewith. The instrument comprises a synchronous motor 124 connected to bus bars 21 by conductors 125. The shaft of motor 124 projects into a casing 126 and is supported in suitable bearings 127 therein. On the shaft is a worm which meshes with a worm wheel 128 mounted on a shaft 129 carried in a suitable bearing 130. Connected to the lower end of shaft 129 is a positive displacement pump 131 which in the present instance is shown as being a pump of the gear type. The suction opening of the pump is indicated at 132 and the discharge opening at 133. Casing 126 is adapted to contain oil or other suitable liquid to a level such as that indicated, whereby the pump is submerged in the liquid. Connected to the upper end of shaft 129 is a fly ball speed governor 134, the weights of which are indicated at 135. The weights are pivoted at 136 and are provided with arms 137 which are connected to a pilot valve 138 which forms a part of a pilot valve structure. Pilot valve 138 rotates with the speed governor and is provided with heads 139 and 140 which control discharge and inlet ports 141 and 142 respectively in a sleeve 143 which surrounds the pilot valve. Pilot valve 138 and sleeve 143 are located in a pilot valve casing 144 which is connected by ports 145 and a passage 146 to the lower end of a cylinder 147. In cylinder 147 is a piston 148 which is connected by a piston rod 149 to a lever 150 pivoted at its outer end on a fulcrum 151 carried on the upper end of a rod 152. Rod 152 is pivoted at its lower end on a fulcrum 153. Pilot valve sleeve 143 is pivotally connected to lever 150 by a rod 154. In cylinder 147 is a stop 155 which limits downward movement of piston 148. Surrounding piston rod 149 and located between the top wall of cylinder 147 and the upper surface of piston 148 is a spring 156 which acts in a direction to oppose upward movement of piston 148 in cylinder 147.

The discharge port 133 of pump 131 is connected by a pipe-line 157 to an admission opening in pilot valve casing 143, which admission opening communicates with ports 142. Connected to pipe-line 157 is a by-pass pipe-line 158 which leads back to tank 126. In by-pass pipe-line 158 is a pressure relief valve 159 of any suitable construction. For example, it may be an adjustable, spring-pressed relief valve of known type, which may be set to maintain the desired pressure in pipe-line 157.

Stem 123 which carries bridge pieces 95^a and 121 is connected to the free end of lever 150. Also, carried by stem 123 is a bridge piece 160 adapted to bridge a pair of contacts 161 in circuit with which is a signal 162 such as a lamp, a bell, or the like.

Synchronous motor 124, being connected to bus bars 21, will rotate at a speed corresponding to the frequency of the line. As a result, speed governor 134 will be driven by motor 124 at a speed corresponding to that of the motor, and weights 135 will position pilot valve 138 at a predetermined position such as that shown in the drawing. Sleeve 143 will have assumed a position wherein heads 139 and 140 shut off the ports 141 and 142. Pump 131 will supply fluid continuously to pipe-line 157 and will maintain therein a definite pressure fixed by the pressure for which relief valve 159 is adjusted. There will have been built up beneath piston 148 a pressure of a value sufficient to raise piston 148 against the action of spring 156 and bring it to the position wherein ports 141 and 142 are covered by valve heads 139 and 140. There thus exists a condition of equilibrium wherein piston 148 and lever arm 150 occupy certain predetermined positions. For normal frequency on the line this may be the positions indicated in the drawing.

If the frequency decreases, the speed of motor 124 decreases a corresponding amount. As a result, governor weights 135 will move inward a definite amount, thus raising pilot valve 138 a corresponding amount and moving head 140 so that it uncovers admission ports 142. Fluid is thus admitted from pipe-line 157 through ports 142, ports 145, and passage 146 to the underside of piston 148, moving it upward and raising lever 150 until sleeve 143 assumes a new and higher position such that ports 142 are again closed by head 140. If the frequency increases, an action similar to that described, except in the opposite direction, takes place. The arrangement is such that when the frequency decreases by a certain predetermined amount, lever 150 will move upward sufficiently to bring bridge piece 160 into engagement with contacts 161, thus operating signal 162. If the frequency decreases further by a predetermined amount, bridge piece 95^a moves from engagement with contacts 94^a, thus opening the circuit through solenoid windings 61 and 91. If the frequency decreases by a further predetermined amount bridge piece 121 is brought into engagement with contacts 120, thus closing the circuit through trip coil 27 to effect the opening of circuit breaker 24 so as to disconnect the auxiliary bus bars 119 from the main bus bars 21. The operation is as follows:

Assume that the parts are in the positions shown in the drawing, the valve means 4 for turbine 1 being open a predetermined amount so that turbine 1 is carrying a certain load, the amount of elastic fluid admitted to the turbine being such that the pressure in the exhaust conduit 3 is at a desired predetermined value. In this connection, it will be understood that the elastic fluid exhausting

from turbine 1 is used for industrial purposes, such as heating or the like, and that the exhaust may be maintained at a value higher or lower than atmospheric pressure. The speed of turbine 1 and its generator 17 will be set by the frequency of the system to which generator 17 is connected, the frequency in turn being set by the main turbine driven generators 22. Speed governor 36 is set for a speed a predetermined amount higher than synchronous speed so that governor 36 is not directly in control of the turbine, pilot valve 39 being in position such that it uncovers ports 43 in pilot valve sleeve 42. Pilot valve 66 occupies a position wherein head 68 covers annular groove 70, thereby preventing flow of oil from pipe-line 72. If now the exhaust pressure in conduit 3 increases, indicating too great a supply of exhaust elastic fluid, the pressure in cylinder 79 beneath piston 78 increases, thereby raising the piston. This will raise the right hand end of lever 76 and lower the left hand end, the lever turning on its fulcrum 89. The lowering of the left hand end of lever 76 lowers the right hand end of lever 64, thus lowering pilot valve 66 and moving head 69 downward, permitting escape of oil from beneath piston 14 by way of pipe 49, ports 45, ports 43 in 42, pipe 47 and annular groove 71. Spring 16 now forces piston 14 downward, thereby moving the valve means 4 toward closed position and decreasing the supply of elastic fluid to turbine 1. When piston 14 moves downward it carries with it the left hand end of lever 58 and raises the right hand end, the lever turning on its fulcrum 59. Raising the right hand end of lever 58 raises link 57 and lifts the left hand end of lever 51. This lowers the right hand end of lever 51 and at the same time the left hand end of lever 64. Lowering the left hand end of lever 64 raises its right hand end and restores pilot valve 66 to its former position wherein head 69 covers annular groove 71 to prevent further escape of liquid from beneath piston 14. The parts thus assume a new position corresponding to the new position of piston 78 and valve means 4. The lowering of the right hand end of lever 51 lowers somewhat pilot valve sleeve 42 but this has no effect on the governing mechanism. If the pressure in conduit 3 decreases, indicating an increased demand for exhaust elastic fluid, piston 78 moves downward in cylinder 79 and effects an opening movement of valve means 4 after the manner just described except that the various parts are moved in the opposite sense. The operation of the mechanism as so far described is that of a known back pressure regulating means. Under normal operating conditions, the frequency of the system remaining substantially constant, the mechanism will continue to operate as described, the turbine 1 functioning as what is known as a back pressure regulated turbine.

If for any reason, the frequency on the main bus bars 21 decreases by a predetermined amount, bridge piece 160 engages contacts 161, thus operating signal 162 to bring the matter to the attention of the operator. If, however, the frequency continues to decrease, then when it reaches a value a predetermined amount lower, bridge piece 95^a 70 will move from engagement with contacts 94^a, thus opening the circuit through solenoid windings 61 and 91. When this occurs, spring 93 will lift the left hand end of lever 76, the lever turning on the upper end of stem 77 as a fulcrum, and will move pilot valve 66 to the upper end of pilot valve casting 67, whereby valve head 68 is moved to uncover annular groove 70. Liquid will be thus admitted from pipe 72 through pipe 47, the pilot valve structure, and pipe 49 to the underside of piston 14, thus tending to move piston 14 upward and tending to open wide valve means 4. At the same time, however, lever 58 will be moved downward by spring 63 in engagement with stop 62, thus lowering the left hand end of lever 51 and raising the right hand end, whereby pilot valve sleeve 42 upward will be sufficient to set the opening of the valve means 4 relative to the position of the speed governor 36 so that full elastic fluid admission at the existing frequency is obtained. The increase in electrical energy thus obtained will tend to restore the frequency of the system to the original value, but as this is accomplished the speed governor may slightly close the valve means 4 until a balance of frequency against electrical demand is obtained. If it is able to do this, then the system will continue to operate with turbine 1 under control of the speed governor 36, the back pressure regulator being now entirely out of control of the turbine.

In connection with the operation just described, it will be seen that the release of fulcrum 89 serves to render inoperative the pressure control piston 78 and that at the same time the movement of fulcrum 59 into engagement with stop 62 serves to change the setting of speed governor 36, the changing of the position of fulcrum 59 being in effect the equivalent of adjusting the length of rod 50.

If, in spite of the efforts of turbine 1, the frequency of the system still continues to fall, then when it reaches a predetermined lower value, bridge piece 121 is brought into engagement with contacts 120, thus energizing trip coil 27 and effecting the opening of circuit breaker 24, thus disconnecting the

130

auxiliary bus bars 19 from the main bus bars 21. Turbine 1 will then continue to operate and maintain the desired frequency on bus bars 19 which have now been segregated from the main system. Bus bars 19 may carry a 5 station load and in addition may carry other load connected to them; or the load connected to bus bars 19 may be any desired load which it is desired especially to maintain.

10 While the back pressure governor is out of action, the excess of exhaust elastic fluid will be discharged past relief valve 29.

15 After the frequency is restored on the main bus bars 21, the turbo-generator set may be then again phased in onto the system through tie switch 24 and the valve gear for turbine 1 may be then reset manually, restoring the parts to the positions for pressure control.

20 The function of the contact making ammeter 101 is to protect generator 17 from an overload in current. This overload may be caused by an excessive power output of the turbine generator set in terms of steam demand from the turbine 1 into the exhaust 25 conduit 3, or it may be produced by the incorrect adjustment of the field of the alternator 17 whereby, due to this incorrect field adjustment, a leading or lagging current in excess of the full load current permitted by 30 the design of the generator 17 may be produced. If the current from the generator increases beyond a predetermined maximum, coil 105 of the contact making ammeter first draws contact arm 102 away from the contacts 103. If now, the current increases still further, coil 105 draws contact arm 102 over until contacts 104 are bridged by contact arm 102, thus permitting current to flow from the upper supply line 94 through conductor 112, 35 contacts 104, conductor 111, field winding 109, armature of the synchronizing motor 56, and conductor 113 to lower supply line 94. This will cause the armature of synchronizing motor 56 to run in a direction to raise bushing 42, 40 and when groove 44 rises above pilot valve head 41, oil will be permitted to escape from beneath piston 14 thereby effecting movement of valve means 4 toward closed position, thus reducing the supply of elastic fluid 45 to the turbine and hence the current output of the generator. This will continue until the current has been reduced to such a value that the reduced force of the coil 105 allows the contact arm 102 to rise from the contacts 104, thereby arresting any further motion of the valve means 4. As there is an intermediate position at which contact arm 102 floats between contacts 103 and 104, there 50 may not be an immediate closing of the contacts 103 by this arm. However, after the conditions in the system have been reestablished to normal, for example by a correction of the field of the alternator 17, then the current from the alternator will drop still 55 further so that the ammeter arm 102 will

bridge the contacts 103. While this has been taking place, the flow of elastic fluid through the valve means 4 may have been curtailed to an extent such that it does not meet the demand for exhaust elastic fluid in conduit 3, with the result that the pressure of the exhaust elastic fluid in conduit 3 will be lower than the desired normal. If the pressure in conduit 3 decreases below a certain value, piston 78 will move to its lowest position and arm 85 will be lowered to an extent such that bridge 86 engages contacts 88. Upon the bridging of these contacts, current may be applied from the upper supply line 94 through conductors 112 and 114, contacts 88, conductor 110, contacts 103, (these having been bridged now by contact arm 102), conductors 108^a, the field coil 108 and the armature of the synchronizing motor, and conductor 113 to the lower supply line 94. Motor 56 now 85 will be operated in a direction to lower pilot valve sleeve 42 to move annular groove 43 below head 40, thereby admitting oil pressure under piston 14 and effecting opening movement of valve means 4. As the valve 90 means 4 is opened, the increase in flow of elastic fluid through turbine 1 will gradually increase the fluid pressure in conduit 3 until the piston 78 rises, opening contacts 88. Further operation of motor 56 will then cease. 95 The pressure, however, may continue to rise because the rise in pressure indicates an increase in the supply of elastic fluid through the valve means 4 beyond that which is demanded by the conduit 3. However, the 100 opening of contacts 88 restores the system to its former operating conditions and the back pressure governor will take control and operate after the manner already described to regulate turbine 1. 105

If, during what may be termed normal back pressure operation, the back pressure governor loads generator 17 to the maximum value of current permitted, then contact arm 102 will be moved from engagement with contacts 103 and stand between contacts 103 and contacts 104. If now the demand for exhaust elastic fluid continues the pressure in conduit 3 will decrease, and may bring bridge 86 into engagement with contacts 88. However, this will not now serve to effect adjustment of the governing mechanism after the manner just described because the circuit is open at contacts 103, these contacts being in series with contacts 88. If this condition should obtain, the load responsive device 105 would function to maintain the turbine fully loaded by operating the synchronizing motor through engagement with contacts 104 and 103. However, as will be clear, it would not 115 be possible for it to adjust the valve means to an extent such that generator 17 would be over loaded.

120 Hand switch 15 may be utilized to effect 125 operation of the synchronizing motor 56 130

manually, being moved into engagement with contact 117 to effect operation of motor 56 in a direction to move sleeve 42 upward, and so effect movement of valve means 4 toward 5 closed position, and being moved in engagement with contact 116 to effect operation of motor 56 in a direction to move sleeve 42 downward and so effect movement of valve means 4 toward open position. In this connection, it will be noted that contacts 103 are 10 in series with contact 116 so that in case generator 17 is already fully loaded valve means 4 cannot be opened further by means of the hand switch because contact arm 102 will not 15 be in engagement with contacts 103. In other words, the hand switch can be utilized to effect opening movement of the valve means only when contact arm 102 bridges contact 103. On the other hand, it may be used to 20 effect closing movement of the valve means at any time.

What I claim as new and desire to secure by Letters Patent of the United States is:—

1. In combination, an elastic fluid turbine, 25 an alternating current generator driven thereby, bus bars to which the alternating current generator is connected, means other than said generator for fixing the frequency of the current on said bus bars, a speed governor for the turbine, said governor being set so that at normal frequency on the bus bars it is not operative to control the turbine, a frequency responsive device, and means controlled by the frequency responsive device 35 for rendering the speed governor operative to control the turbine in case the frequency on the bus bars decreases below a predetermined low value.

2. In combination, an elastic fluid turbine, 40 an alternating current generator driven thereby, bus bars to which the alternating current generator is connected, means other than said generator for fixing the frequency of the current on said bus bars, a speed governor for the turbine, said governor being set so that at normal frequency on the bus bars it is not operative to control the turbine, means responsive to a condition of operation other than the speed of the turbine for normally controlling the admission of elastic fluid to the turbine, and means for transferring the control of the turbine from said last named means to the speed governor in case the frequency on the bus bars decreases below a predetermined low value.

3. In combination, an elastic fluid turbine, 45 an alternating current generator driven thereby, auxiliary bus bars to which the alternating current generator is connected, main bus bars, means connecting the auxiliary bus bars to the main bus bars, means connected to the main bus bars for fixing the frequency of the current on said bus bars, a speed governor for the turbine, said governor being set so that at normal frequency on the bus

bars it is not operative to control the turbine, a frequency responsive device, and means controlled by the frequency responsive device for segregating the auxiliary bus bars from the main bus bars in case the frequency on the main bus bars decreases below a predetermined low value.

4. In combination, an elastic fluid turbine, an alternating current generator driven thereby, auxiliary bus bars to which the alternating current generator is connected, main bus bars, means connecting the auxiliary bus bars to the main bus bars, means connected to the main bus bars for fixing the frequency of the current on said bus bars, a speed governor for the turbine, said governor being set so that at normal frequency on the bus bars it is not operative to control the turbine, means for varying the setting of the speed governor when the frequency on the bus bars decreases below a predetermined value whereby the turbine tends to take on full load, and means for segregating the auxiliary bus bars from the main bus bars in case the frequency decreases to a still lower value.

5. In combination, an elastic fluid turbine, an alternating current generator driven thereby, auxiliary bus bars to which the alternating current generator is connected, main bus bars, means connecting the auxiliary bus bars to the main bus bars, means connected to the main bus bars for fixing the frequency of the current on said bus bars, a speed governor for the turbine, said governor being set so that at normal frequency on the bus bars it is not operative to control the turbine, means for varying the setting of the speed governor when the frequency on the bus bars decreases below a predetermined value whereby the turbine tends to take on full load, and means responsive to the current flowing from said generator for limiting the current load which can be placed on the generator by the turbine.

6. In combination, an elastic fluid turbine, 110 an alternating current generator driven thereby, bus bars to which the alternating current generator is connected, means other than said generator for fixing the frequency of the current on said bus bars, a speed governor for the turbine, said governor being set so that at normal frequency on the turbine it is not operative to control the turbine, means responsive to a condition of operation other than the speed of the turbine for normally controlling the admission of elastic fluid to the turbine, and means for automatically rendering the speed governor operative to control the turbine and for changing the setting of the speed governor in case the frequency on the bus bars decreases below a predetermined low value.

7. In combination, an elastic fluid turbine, 115 an alternating current generator driven thereby, bus bars to which the alternating

current generator is connected, means other than said generator for fixing the frequency of the current on said bus bars, a speed governor for the turbine, said governor being set so that at normal frequency on the turbine it is not operative to control the turbine, means responsive to a condition of operation other than the speed of the turbine for normally controlling the admission of elastic fluid to the turbine, and means for automatically changing the setting of the speed governor and transferring the control of the turbine from said last named means to the speed governor in case the frequency on the bus bars decreases below a predetermined low value.

8. In combination, an elastic fluid turbine, an alternating current generator driven thereby, auxiliary bus bars to which the alternating current generator is connected, main bus bars, means connecting the auxiliary bus bars to the main bus bars, means connected to the main bus bars for fixing the frequency of the current on said bus bars, a speed governor for the turbine, said governor being set so that at normal frequency on the bus bars it is not operative to control the turbine, means responsive to a condition of operation other than the speed of the turbine for normally controlling the admission of elastic fluid to the turbine, means for automatically changing the setting of the speed governor and transferring the control of the turbine from said last named means to the speed governor in case the frequency on bus bars decreases below a predetermined low value, and means for segregating the auxiliary bus bars from the main bus bars in case the frequency decreases to a still lower value.

40 9. In combination, an elastic fluid turbine, an alternating current generator driven thereby, bus bars to which the alternating current generator is connected, means other than said generator for fixing the frequency of the current on said bus bars, a speed governor for the turbine, said governor being set so that at normal frequency on the bus bars it is not operative to control the turbine, means including a lever through which the governor effects changes in the amount of elastic fluid supplied to the turbine, and means for changing the position of the fulcrum of said lever to vary the setting of the speed governor when the frequency on the bus bars decreases below a predetermined low value.

10. In combination, an elastic fluid turbine, an alternating current generator driven thereby, bus bars to which the alternating current generator is connected, means other than said generator for fixing the frequency of the current on said bus bars, a speed governor for the turbine, said governor being set so that at normal frequency on the bus

bars it is not operative to control the turbine, means including a lever through which the governor effects changes in the amount of elastic fluid supplied to the turbine, a magnetically controlled fulcrum for said lever, and means for changing the position of said fulcrum to vary the setting of the speed governor when the frequency on the bus bars decreases below a predetermined low value.

11. The combination with an elastic fluid turbine having valve means for controlling the flow of elastic fluid thereto, of control means for positioning said valve means comprising a speed responsive governor and a governor responsive to the pressure of elastic fluid flowing from the turbine, means for adjusting the setting of the speed governor, and means controlled by said pressure responsive governor for adjusting the speed governor setting means to effect opening of the valve means when the pressure of the elastic fluid flowing from the turbine is below a certain low value.

12. The combination with an elastic fluid turbine having valve means for controlling the flow of elastic fluid thereto, of control means for positioning said valve means comprising a speed responsive governor and a governor responsive to the pressure of elastic fluid flowing from the turbine, means for adjusting the setting of the speed governor, means controlled by said pressure responsive governor for adjusting the speed governor setting means to effect opening of the valve means when the pressure of the elastic fluid flowing from the turbine is below a certain low value, and means for rendering last said means inoperative when turbine is fully loaded.

13. The combination with an elastic fluid turbine having valve means for controlling the flow of elastic fluid thereto, and an alternating current generator driven by said turbine, of control means for positioning said valve means comprising a speed responsive governor and a governor responsive to the pressure of elastic fluid flowing from the turbine, means for adjusting the setting of the speed governor, means controlled by said pressure responsive governor for adjusting the speed governor setting means to effect opening of the valve means when the pressure of the elastic fluid flowing from the turbine is below a certain low value, and means responsive to the current delivered by the generator for rendering said last named means inoperative when such current exceeds a predetermined high value.

14. The combination with an elastic fluid turbine having valve means for controlling the flow of elastic fluid thereto, and an alternating current generator driven by said turbine, of control means for positioning said valve means comprising a speed responsive governor and a governor responsive to the

pressure of elastic fluid flowing from the turbine, means for adjusting the setting of the speed governor, means responsive to the current load on the generator for adjusting the speed governor setting means in a direction to effect closing of said valve means when the current load exceeds a predetermined high value, means controlled by said pressure responsive governor for adjusting the speed governor setting means to effect opening of the valve means when the pressure of the elastic fluid flowing from the turbine is below a certain low value, and means responsive to the current delivered by the generator for rendering said last named means inoperative when such current exceeds a predetermined high value.

15. The combination with a turbine driven set comprising an elastic fluid turbine having valve means for controlling the flow of elastic fluid thereto, of a speed governor for the turbine, means for adjusting the setting of the speed governor, a second governing means for the turbine, said second governing means normally controlling the supply of elastic fluid to the turbine, and means responsive to an abnormal operating condition of said set for rendering inoperative said second governing means and adjusting the setting of the speed governor.

16. The combination with an elastic fluid turbine, a dynamo-electric machine connected to the turbine, and alternating current bus bars to which the dynamo electric machine is connected and which serve normally to fix the speed of the turbine of a speed governor for the turbine, said governor being set normally for a speed higher than that defined by the frequency on the alternating current bus bars, a second governing means for said turbine, said second governing means normally controlling the supply of elastic fluid to the turbine, and means responsive to an abnormal operating condition for rendering inoperative said second governing means and adjusting the setting of the speed governor in a direction to effect opening of the valve means.

In witness whereof, I have hereunto set my hand this 19th day of February, 1929.

REGINALD G. STANDERWICK.

CERTIFICATE OF CORRECTION.

Patent No. 1,759,763.

Granted May 20, 1930, to

REGINALD G. STANDERWICK.

* It is hereby certified that error appears in the printed specification of the above numbered patent requiring correction as follows: Page 2, line 128, for the word "is" read "in"; page 3, line 54, for "thereby" read "there by"; page 4, line 3, for "Serial No. 314,917" read "Serial No. 341,917"; and that the said Letters Patent should be read with these corrections therein that the same may conform to the record of the case in the Patent Office.

Signed and sealed this 22nd day of July, A. D. 1930.

(Seal)

Wm. A. Kinnan,
Acting Commissioner of Patents.
